UNITED STATES PATENT OFFICE.

JOHN WOLCOTT PARMELEE AND CHARLES JAMES COOPER, OF WILKES-BARRÉ, PENNSYLVANIA.

FURNACE FOR HEATING VEHICLE-AXLES.

SPECIFICATION forming part of Letters Patent No. 392,223, dated November 6, 1888.

Application filed April 5, 1887. Serial No. 233,770. (No model.)

To all whom it may concern:

Be it known that we, JOHN WOLCOTT PARMELEE and CHARLES JAMES COOPER, citizens of the United States, residing at Wilkes-Barré, 5 in the county of Luzerne and State of Pennsylvania, have invented a new and useful Improvement in Furnaces for Heating Vehicle-Axles, of which the following is a specification.

10 Our invention relates to an improvement in furnaces for heating vehicle-axles preparatory to forging the same; and it consists in the peculiar construction and combination of devices that will be more fully set forth herein- 15 after, and particularly pointed out in the claim.

The object of our invention is to construct a furnace especially adapted to burn "buckwheat" and culm coal. It is well known in the art that this grade of coal is very dense, 20 and in order to burn it the coal must be spread over a large area and not be packed too deep. If the column of coal is too high in the furnace, the density of the column prevents the free passage of air to assist combustion. By 25 spreading the coal over a wide area we are enabled to place a large quantity of coal in the furnace without having the column of coal too deep, and thus the air is permitted to pass up through the coal for the purposes well under- 30 stood in the art.

Another feature of our invention is the inclination of the walls of the combustion-chamber, against which walls the cold air strikes to secure perfect combustion.

35 Another feature is the construction of the furnace so that the smoke and all products of combustion pass out through the opening below the arch where the metal is inserted. By this arrangement all the heat is concentrated 40 at the point where it will do the most good, and none of the heat can escape from the furnace without acting on the metal inserted through the opening below the arch.

In the drawings, Figure 1 is a vertical sectional view of a furnace embodying our improvements. Fig. 2 is partly a top plan view and partly a sectional view of the same, taken on the line *x x* of Fig. 1.

A represents a furnace, which is built of 50 fire-brick, and is provided in its lower side

with an ash-pit, B, and a combustion-chamber, C, arranged above the ash-pit. Near the outer sides of the furnace are a series of communicating chambers, D, which are kept supplied with running water, in order to reduce 55 the temperature in the outer sides of the furnace. The combustion-chamber C is larger at its lower side than at its upper side, and the side walls, E, of the said chamber converge 60 upwardly, as shown in Fig. 1.

F represents the grate, which is arranged in the lower side of the combustion-chamber, and forms the bottom thereof.

G represents an opening, which is made in the rear side of the furnace at a suitable 65 distance above the grate, and H represents a hopper or chute which communicates with the opening G and with the combustion-chamber. The lower side of this hopper or chute is inclined downwardly from the lower side of the 70 opening G to a point slightly above the grate, and the upper side of the hopper or chute is inclined upwardly from the upper side of the opening G to a point slightly below the upper side of the combustion-chamber. The opening G is normally closed by the usual door, I.

On the upper side of the furnace is a metallic plate, K, which covers the brick of which the furnace is composed and protects the same 75 from injury.

L represents an arch, made of fire-brick and erected over the combustion-chamber. In one side of the lower portion of the arch are made a series of openings, M, through which bars or rods of metal may be introduced below the 85 arch L and above the combustion-chamber, and thereby be subjected to the heat ascending from the combustion-chamber before being forged.

In the front side of the furnace is a tuyere, 90 N, which communicates with the ash-pit below the grate, and to which a blast of air is introduced to cause active combustion of the fuel. Coal is supplied to the fire through the opening G and a hopper or chute, H.

By making the combustion-chamber larger at its lower side than at its upper side, and providing the same with the upwardly-converging inclined walls E, the hot air which arises from the fire strikes against the inclined 100

sides of the combustion-chamber and is deflected toward the center thereof and becomes mingled with the gases arising from the fire, and the heat is intensified under the arch. 5 The result is that the bars or rods of metal arranged over the combustion-chamber are heated very rapidly and very thoroughly.

We design our furnace more particularly for use in heating vehicle-axles preparatory to forging the same, but do not limit ourselves to its use for this particular purpose.

In practice, the products of combustion pass out through the opening M, where the metal is inserted. We usually employ a hood to 15 cover the furnace, and said hood has a smoke-stack to carry off products of combustion.

We usually construct the furnace so that the distance from the grate to the working-surface of the furnace is about thirteen inches, more or 20 less. It is well known that the flame from culm coal does not rise very high, and hence it is necessary not to make the distance between the grate and the working-surface too great. By our arrangement the heat is brought 25 into intimate and direct contact with the material to be acted upon.

By having walls E inclined the culm coal cannot collect in the corners or at the sides and not become burned.

30 We do not wish to be understood as claiming, broadly, the use of inclined walls for the combustion-chamber of a furnace, as we are aware that this is, broadly, old; but prior devices of this character have always employed a smoke 35 stack or flue to carry off the products of combustion.

In our furnace we use no smoke stack or flue, but have the products of combustion pass out through the opening M, through which the metal is inserted to be heated. Thus all the heat must strike the arch L and also act on the material to be heated. Where a separate smoke-flue is employed, a great portion of the heated products of combustion pass out through such flue without acting on the material to be heated. The improvement made by us in this respect is manifest.

Having thus described our invention, we claim—

In a furnace for heating metal, the combustion-chamber having the upwardly-converging inclined walls E, the arch L, spanning the top of the combustion-chamber, so that the products of combustion rising from the chamber must strike the arch, and the opening M at the base of the arch, said opening serving 55 the double function of providing the sole outlet for the smoke and products of combustion and also as the entrance-opening for the introduction of the bars of metal, whereby the smoke and products of combustion must pass 60 out the opening through which the metal to be heated is inserted, as set forth.

In testimony that we claim the foregoing as our own we have hereto affixed our signatures in presence of two witnesses.

JOHN WOLCOTT PARMELEE.

CHARLES JAMES COOPER.
